UNITED STATES PATENT OFFICE

119,193

DESIGN FOR A TORQUE MEASURING WRENCH

Herman W. Zimmerman, Highland Park, Ill., as-
signor, by mesne assignments, to Automotive
Maintenance Machinery Co., North Chicago,
Ill., a corporation of Illinois

Application July 1, 1939, Serial No. 85,798

Term of patent 7 years

To all whom it may concern:

Be it known that I, Herman W. Zimmerman, a citizen of the United States, residing at Highland Park, in the county of Lake, State of Illinois, have invented a new, original, and ornamental Design for Torque Measuring Wrench, of which the following is a specification, reference being had to the accompanying drawing, forming a part thereof, wherein—

Fig. 1 is a perspective view of a torque measuring wrench showing my new design; and

Fig. 2 is an enlarged bottom plan view of the handle portion of the same.

The dominant feature of the design resides in the handle portion.

I claim:

The ornamental design for a torque measuring wrench, as shown and described.

HERMAN W. ZIMMERMAN.
